UNITED STATES PATENT OFFICE.

CLARENCE B. FOWLER, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed September 8, 1920. Serial No. 408,887.

To all whom it may concern:

Be it known that I, CLARENCE B. FOWLER, a citizen of the United States, residing at New York, in the county of New York and 5 State of New York, have invented certain new and useful Improvements in Telephone-Exchange Systems, of which the following is a full, clear, concise, and exact description.

10 This invention relates to telephone exchange systems and more particularly to such systems in which connections between telephone lines terminating at manual exchanges and telephone lines terminating at 15 automatic exchanges, are established by way of cord and trunk circuits over which automatic switches are controlled from the manual exchange for effecting connections.

20 The object of this invention is the production of improved talking and signaling circuits for a system of this nature and also to provide for complete supervision over the connections for the operator at the manual exchange.

25 One of the features of the invention consists in providing a repeating trunk circuit with capacity which may be reduced to a fixed minimum under the control of the operator to provide an efficient signaling circuit during the establishment of a connection, and increased to a fixed maximum under the control of a called subscriber to provide an efficient talking circuit.

30 Another feature of the invention consists in such an arrangement of circuits and apparatus that the called subscriber not only controls the varying of capacity to provide an efficient talking circuit, but also controls means for furnishing the operator with 35 complete supervision of the connection.

35 In the drawings Fig. 1 represents a circuit arrangement of a semi-automatic telephone exchange system embodying the invention, only so much being shown of the 40 circuits and apparatus as is necessary for a clear understanding of the present invention. Fig. 2 shows a modification of Fig. 1.

45 There is shown in Fig. 1 of the drawings a telephone line A which terminates at the manual exchange where it may be connected with a cord circuit B in any suitable and well-known manner. The calling end of the 50 cord circuit may be connected with a trunk circuit T extending from the manual to the

automatic exchange, at which are provided 55 the usual selector and connector switches for effecting connection between the trunk circuit and telephone lines, such as D, terminating at the automatic exchange. The apparatus shown to the left of the dotted line 1-1 is located at the manual exchange and to the right thereof at the automatic exchange. The trunk circuit T comprises inner and outer sections normally inductively united by means of a large capacity condenser 14. A small capacity condenser 15 is normally disconnected from the trunk circuit, but it may be connected to the trunk circuit under the control of the operator and disconnected from the trunk circuit under the control of the called subscriber such as D.

55 Referring to Fig. 2 of the drawings there is shown a telephone line E which terminates at the manual exchange where it may be connected with a cord circuit F in any suitable and well-known manner. The calling end of the cord circuit F may be connected with a trunk circuit T¹ extending from the manual to the automatic exchange, 60 at which are provided the usual selector and connector switches for effecting connections between the trunk circuit and the telephone lines, such as G, terminating at the automatic exchange. The apparatus shown to 65 the left of the dotted line 2-2 is located at the manual exchange and that to the right thereof at the automatic exchange. The trunk circuit T¹ comprises inner and outer sections normally inductively united by 70 means of large capacity condensers 121 and 124. Small capacity condensers 122 and 123 are normally disconnected from the trunk circuit T¹, but may be connected to the trunk circuit under the control of the operator and 75 then disconnected therefrom under the control of the called subscriber.

80 The nature of the invention is such that it is believed a clear understanding thereof may be had from the following detailed description and the appended claims.

85 Referring to Fig. 1 of the drawings and assuming that the subscriber at the station on the telephone line A has initiated a call, and that the answering end of the cord 90 circuit B has been associated therewith in any well-known manner, the operator actuates listening key 5 thereby connecting the

- operator's telephone set (not shown) in circuit so that the operator may converse with the calling subscriber to ascertain the number of the line with which connection is desired. Ascertaining that connection is desired with telephone line D, which terminates at the automatic exchange, the operator inserts calling plug 6 of the cord circuit B into jack 7 of the trunk circuit T. Calling supervisory lamp 8 of the cord circuit B is lighted over a path extending from grounded battery, through lamp 8, resistance 10, sleeves of plug 6 and jack 7 and coil 9 to ground. Relay 44 of the trunk circuit T operates over a circuit traceable from grounded battery, winding of relay 44, left-hand normal contacts of relay 46, tips of jack 7 and plug 6, upper normal contacts of relay 22, upper normal contacts 20 or ringing key 42, and upper right-hand winding of repeating coil 50 to ground. The operation of relay 44 bridges polarized relay 13 in multiple with the non-inductive resistance 45 across the talking conductors 25 of the outer section of the trunk over a path traceable from conductor 60, through the winding of polarized relay 13 in parallel with the back contact and armature of relay 46 and resistance 45 to conductor 61, for 30 the purpose of operating a non-numerical switch (not shown) at the automatic exchange to extend the trunk T to an idle connector C. As soon as the connection is extended to the connector C, line relay 35 thereof is energized over a path extending from grounded battery, left-hand winding of relay 35, outer normal contacts of relay 36, conductor 61, front contact and armature of relay 44, through resistance 45 and right-hand armature and back contact of relay 46 in parallel with the winding of the polarized relay 13 to conductor 60, inner normal contacts of relay 36, and right-hand winding of relay 35 to ground. Polarized relay 13 45 does not operate at this time since the direction of flow of current through its windings is such as to prevent its operation. The operator may now actuate the impulse sender S, which is common to the cord 50 circuits of her position. Upon the initial actuation of the impulse sender S, the off normal contacts 21 thereof close, causing the operation of relay 25 which remains operated during the transmission of each 55 series of impulses. Relay 25 in operating, causes the operation of connecting relay 22 of the cord circuit B and switching relay 11 of the trunk circuit T over a circuit traceable from ground, armature and back contact of relay 23, front contact and left-hand armature of relay 25, outer lower contacts of key 5, lower normal contacts of key 42, inner lower normal contacts and winding of relay 22, rings of plug 6 and jack 7, armature and back contact of polarized relay 13, and winding of relay 11 to grounded battery. Relay 22 in operating locks up in series with relays 23 and 11 over a path traceable from ground, winding of relay 23, contacts of key 26, lower inner 70 armature and front contact and winding of relay 22, rings of plug 6 and jack 7, armature and back contact of polarized relay 13 and winding of relay 11 to grounded battery. The operation of relay 22 opens the 75 talking conductors of the cord circuit B and connects ground through the impulse contacts 20 of the sender S to relay 44 to hold said relay 44, which was previously energized, operated. The energization of 80 the pilot relay 23 resulting from closure of the locking circuit of relay 22, opens a contact in the original energizing circuit of relay 22 and causes lamp 28 to be lighted indicating to the operator that the impulses sender S has been rendered individual 85 to the cord circuit and connected therewith. As soon as pilot lamp 28 lights the operator may restore key 5 to normal. The operation of relay 11 disconnects the 90 large capacity condenser 14 from the talking conductors of the trunk circuit T and connects the small capacity condenser 15 thereto, so that the large capacity condenser will not interfere with the transmission of impulses and still provide a path for the transmission of tones from the automatic exchange back to the calling subscriber as well as to the operator. Relay 22 of the 95 cord circuit and relay 11 of the trunk circuit after being operated remain locked up until released by the operator actuating key 26 or until polarized relay 13 energizes upon the response of the called subscriber. The opening and closing of the impulse 100 contacts 20 of the sender S during the return movement of the sender to its normal position causes the opening and closing of the circuit of impulse repeating relay 44. Each time relay 44 deenergizes in response 105 to the opening of its circuit, the bridge across the outer section of the trunk circuit T will be interrupted thereby causing the deenergization of impulse relay 35 of the connector C. The impulse relay 35 of 110 the connector C, controls the usual motor magnets for the connector whereby the brushes 38 and 39 of the connector are set upon the terminals 50 and 51 of the telephone line D. The subscriber at station D 115 may be signaled in a manner well known in the art. Tones, indicating to the calling subscriber 120 that a station is being signaled or in case the calling line D had been busy and a 125 source of busy tone had been connected to the trunk conductors 60 and 61 in any manner well known in the art will be transmitted to the calling subscriber or to the operator even though the talking conductors 130

of the trunk and cord circuit are opened, over a path traceable from conductor 61 through the front contact and armature of relay 44, lower alternate contacts of relay 5 11, small capacity condenser 15, rings of jack 7 and plug 6, condenser 4, lower normal contacts of ringing key 42, and thence to the operator's telephone set or through the winding of supervisory relay 41 and lower 10 right-hand winding of repeating coil 50 to grounded battery. The tone passing through the secondary winding of repeating coil 50 is induced into the primary winding thereof and passes through supervisory 15 relay 56 over the line loop of line A to the subscriber thereat. The operator and the calling subscriber are thus supplied with a path for the reception of tones from the distant exchange, which is independent of the 20 normal talking conductors extending from said subscriber to said distant exchange.

The subscriber of telephone line D in responding to the calling signal causes the energization of reversing relay 36. The energization of relay 36 reverses the battery connections of the talking conductors of the trunk circuit whereby polarized relay 13, bridged across the outer section of the trunk circuit T, is energized and opens its 25 back contact. The opening of this contact interrupts the locking circuit of relays 23, 22 and 11, whereupon these relays deenergize. The deenergization of relay 23 opens the circuit of and extinguishes pilot lamp 28; the deenergization of relay 22 disconnects the sender S from the cord circuit B, renders the talking conductors of the cord circuit continuous, and short-circuits condenser 4; and the deenergization of relay 11 30 disconnects the small capacity condenser 15 from, and connects the large capacity condenser 14 to the talking conductors of the trunk circuit T.

The energization of polarized relay 13 45 also bridges relay 46 across the talking conductors of the inner section of the trunk thereby causing the operation of supervisory relay 41 of the cord circuit B over a circuit traceable from ground, upper right-hand winding of repeating coil 50, upper normal contacts of relay 22, tips of plug 6 and jack 7, winding of relay 46, front contact and armature of polarized relay 13, rings of jack 7 and plug 6, back contact and 50 lower outer armature of relay 22, lower normal contacts of ringing key 42, winding of supervisory relay 41, and lower right-hand winding of repeating coil 50 to grounded battery. Relay 41 in energizing shunts supervisory lamp 8, thereby causing the extinguishing of said lamp, which indicates to the operator that the called party has responded.

Relay 46 is energized over the circuit just traced and in attracting its left-hand arma-

ture, substitutes a local ground for maintaining impulse responsive relay 44 in place of the ground at the contacts 20 of impulse sender S, and in attracting its right-hand armature removes the non-inductive resistance 45 from parallel relationship with the winding of polarized relay 13.

Prior to the response of the called subscriber at the telephone line D, the operator may free the impulse sender S from connection with the cord circuit B by actuating key 26. Opening of the contacts of the key 26, interrupts the locking circuit for relays 23, 22 and 11 in the manner before described, thereby disconnecting the sender S 75 from the cord circuit; rendering the talking conductors of the cord circuit continuous; substituting the small for the large capacity condenser; and extinguishing pilot lamp 28. If, after the operator actuates the key 26, the subscriber of station D responds by removing the receiver from the switchhook, the energization of reversing relay 36 causes the operation of polarized relay 13. The operation of relay 13 bridges relay 46 across 80 the talking conductors of the inner section of the trunk, whereupon supervisory relay 41 energizes thereby extinguishing the supervisory lamp 8.

At the conclusion of conversation the subscribers restore their receivers to the switchhooks. The restoration of the receiver to the switchhook at the station on the telephone line D, causes the deenergization of reversing relay 36, whereupon the connection of battery and ground with the talking conductors of the trunk circuit is reversed, causing the release of polarized relay 13. Relay 46 is removed from bridged relation with the talking conductors of the inner section of the trunk and supervisory relay 41 deenergizes, permitting the lighting of the supervisory lamp 8 which now serves as a disconnect signal to the operator at the manual office. The operator may thereupon disconnect the plug 6 from the jack 7 whereupon all apparatus associated with the calling end of the cord circuit B of the trunk circuit T is released and restored to normal position, thereby releasing the switches at the automatic exchange.

Referring to Fig. 2 of the drawings and assuming that the subscriber at telephone line E has initiated a call and the answering end of the cord circuit F has been associated therewith in any well-known manner, the operator actuates a listening key (not shown) thereby connecting the operator's telephone set (not shown) in circuit so that the operator may converse with the calling subscriber to ascertain the number of the line with which connection is desired. Assuming that connection is desired with telephone line G, the operator may restore the key to normal and then insert calling plug 110 115 120 125 130

106 of the cord circuit F into jack 107 of the trunk circuit T¹. Relay 115 of the cord circuit F and sleeve relay 120 of the trunk circuit T¹ are thereupon energized over a path 5 extending from grounded battery, through the winding of relay 115, winding of marginal relay 112 which is not energized at this time, normal contacts of relay 114, sleeves of plug 106 and jack 107 and winding of relay 10 120 to ground. Relay 115 in operating disconnects the usual test lead to the operator's telephone set from the tip of the cord circuit and renders the talking conductors of the cord circuit continuous. Relay 112 is of the 15 marginal type and does not operate in series with relay 120, which has a high resistance winding.

Impedance coils 109 and 110 therefore remain bridged across the talking conductors 20 of the cord when a connection is established with the trunk circuit T¹. The particular cord circuit herein shown is adaptable for use with other trunk circuits which do not have a resistance such as the winding of relay 120 connected to the sleeve of the jack in which case, the marginal relay 112 operates thereby disconnecting the impedance coils 109 and 110 from bridged relationship with the cord circuit. Relay 120 in operating establishes a circuit for the energization of 25 slow-to-release relay 118 over a path extending from grounded battery, through the inner armature and front contact of relay 120 and through the winding of relay 118 to ground. Relay 120 in operating also bridges the winding of polarized relay 126 across the 30 outer section of the trunk thereby causing the operation of a non-numerical switch (not shown) at the automatic exchange for the purpose of extending the trunk to an idle 35 connector switch such as K at the automatic exchange.

Impulses relay 128 at the connector K thereupon operates over a path extending from 40 grounded battery, left-hand winding of relay 128, outer left-hand normal contacts of relay 129, conductor 131, outer right-hand armature and front contact of relay 120, winding of polarized relay 126, conductor 45 130, inner normal contacts of relay 129 and right-hand winding of relay 128 to ground. Polarized relay 128 does not operate at this time since the direction of flow of current 50 through its winding is such as to prevent its operation.

The operation of slow-to-release relay 118 causes the operation of relays 116 and 125 over a path extending from grounded battery, left-hand armature and front contact 55 of relay 118, windings of relay 116 and 125 in parallel to ground at the back contact and armature of relay 126. Relays 116 and 125 in operating disconnect the large capacity condensers 121 and 124 from the tip and 60 ring talking conductors of the trunk circuit

T¹, respectively, and connect the small capacity condensers 122 and 123 thereto. Relay 116 in operating also connects ground and battery to the tip and ring talking conductors of the inner section of the trunk 70 circuit T¹, respectively, thereby causing the operation of supervisory relay 108 of the cord circuit over a path extending from ground, left-hand winding of retardation coil 117, upper alternate contacts of relay 75 116, tips of jack 107 and plug 106, armature and front contact of relay 115, coil 110, back contact and armature of relay 112, winding of relay 108, coil 109, rings of plug 106 and jack 107, lower alternate contacts of relay 80 116, and right-hand winding of retardation coil 117 to grounded battery. Relay 108 in operating completes a circuit at its armature and front contact for the lighting of supervisory lamp 111. Relay 125 of the 85 trunk circuit T¹ in operating bridges non-inductive resistance 127 across the outer section of the trunk in parallel with the winding of polarized relay 126.

The operator may now actuate the monitoring and dialing key 105, which is provided for each of the cord circuits, F, in addition to the listening key therefor, heretofore referred to upon actuation of key 105, relay 114 is energized over a path extending 90 from ground, through contacts 101 of key 105 and winding of relay 114 to grounded battery. Relay 114, in operating, connects the impulse sender S¹ to the sleeve of the cord circuit through its inner armature and 95 front contact and connects ground through resistance 113 at its outer armature and front contact to relays 112 and 115 in order to hold relay 115 energized.

The operator may now actuate the impulse sender S¹ in order to set the brushes of switch K upon the terminals of the desired telephone line G. Each interruption of the contacts 140 of the impulse sender S causes the release of repeating relay 120 of the 110 trunk circuit T¹ which in retracting its armatures opens the bridge across the outer section of the trunk, thereby releasing impulse responsive relay 128 of the connector K. Relay 118 being slow-to-release does not retract its armature during the sending of a series of impulses and relays 116 and 125 are thereby maintained energized. The impulse responsive relay 128 of the connector switch K controls the usual motor magnets 115 for the connector at the automatic exchange under the control of which the brushes 138 and 139 of the connector K are set upon the terminals 150 and 151 of the telephone line G. The call bell at the station 120 of telephone line G may be actuated in the usual manner and the subscriber in responding to the operation thereof, removes the receiver from the switchhook causing the energization of reversing relay 129. The energization 125 of reversing relay 129 causes the connection 130 of telephone line G to the trunk circuit T¹ and the connection of the trunk circuit T¹ to the telephone line G.

- gization of relay 129 reverses the battery connections to the talking conductors of the trunk circuit, whereby polarized relay 126, bridged across the talking conductors 5 of the trunk circuit T^1 is energized and opens its contact. The opening of this contact interrupts the locking circuits for relays 116 and 125. Relays 116 and 125 thereupon release. Relay 116 in retracting its armatures 10 renders the talking conductors of the trunk circuit T^1 continuous, thereby disconnecting the small capacity condensers from the trunk circuit and connecting the large capacity condensers 121 and 124 thereto. Relay 116 15 in retracting its armatures also disconnects ground and battery from the tip and ring talking conductors of the inner section of the trunk circuit T^1 , thereby causing the release of supervisory relay 108 of the cord circuit F and the consequent extinguishing 20 of the supervisory lamp 111, which indicates to the operator that the called party has responded. Relay 125 in releasing removes the non-inductive resistance 127 from 25 parallel relationship with the winding of polarized relay 126 and disconnects the small capacity condensers 122 and 123 from the talking conductors of the outer section of the trunk circuit T^1 .
- 30 Up until the time that the called subscriber of telephone line G responds, a path for tones, such as a busy signal tone or a ringing signal tone exists over the trunk circuit T^1 and the connected cord circuit F for the operator and the calling subscriber of the telephone line E over a path traceable from conductor 131, through the lower armature and front contact of relay 125, condenser 123, lower alternate contacts of relay 35 116, rings of jack 107 and plug 106 and thence through the calling substation loop or the operator's telephone set, to the front contact and armature of relay 115, tips of plug 106 and jack 107, upper alternate contacts 40 of relay 116, condenser 127, upper alternate contacts of relay 125 to conductor 130. The operator and subscriber are thus supplied with a path for the reception of tones from the distant exchange, which is independent 45 of the normal talking circuits extending from said subscriber to said distant exchange.
- 50 At the conclusion of conversation the subscribers restore their receivers to the switchhooks. The restoration of the receiver to the switchhook at the station of telephone line G causes the deenergization of reversing relay 129, whereupon the connections of battery and ground with the talking 55 conductors of the trunk circuit are reversed causing the release of polarized relay 126. Relay 126 in deenergizing again completes a circuit for relays 116 and 125 over paths previously traced. Relay 116 in operating 60 connects ground and battery to the talking 65 conductors of the trunk circuit, thereby causing the energization of relay 108 as before described and the consequent lighting of supervisory lamp 111, which now serves as a disconnect signal to the operator at the 70 manual office. The operator will thereupon disconnect the plug 106 from the jack 107, whereupon all apparatus associated with the calling end of the cord circuit F and with the trunk circuit T^1 is released and restored to normal position. Opening of the bridge across the outer section of the trunk circuit T^1 causes the release of the switch 75 at the automatic exchange.
- What is claimed is:
1. In a telephone exchange system, a called line, an operator's cord circuit, a trunk circuit and automatic switches for establishing a connection with said line, capacity in said trunk circuit, a supervisory signal in 80 said cord circuit, means controlled by the operator for varying said capacity, and means controlled by the called line for varying said capacity and for actuating said signal.
  2. In a telephone exchange system, a calling line at a manual exchange, a called line at an automatic exchange, means including an operator's cord circuit, a trunk circuit and automatic switches for establishing a connection between said lines, capacity for 85 said trunk circuit, and means controlled by the operator and the subscriber of the called line for varying said capacity.
  3. In a telephone exchange system, a called line, a trunk circuit, means including an impulse sender and automatic switches for establishing a connection over said trunk circuit with said line, capacity in said trunk circuit, means responsive to the actuation of the impulse sender for varying said capacity and means controlled by the called line for 90 varying said capacity.
  4. In a telephone exchange system, a trunk circuit, a cord circuit connected therewith, an impulse sender, means responsive to the actuation of said sender for connecting it with the cord circuit, capacity in said trunk circuit, a telephone line, and a relay in said trunk circuit for varying said capacity and 95 for causing the disconnection of said sender from said cord circuit, said relay being controlled by said telephone line.
  5. In a telephone exchange system, a trunk circuit, a cord circuit connected therewith, an impulse sender, means responsive to the actuation of said sender for connecting it with the cord circuit, a telephone line, a supervisory signal in said circuit, capacity in said trunk circuit, and means controlled by said telephone line for 100 disconnecting said sender from said cord circuit, actuating said supervisory signal and varying said capacity.
  6. In a telephone exchange system, a cord 105

circuit, a called line, means including a two-conductor trunk circuit for establishing a connection to said called line, a large capacity condenser normally connected in said 5 trunk circuit, a small capacity condenser normally disconnected from said trunk circuit, means controlled by said sender for substituting the small for the large capacity condenser, and means controlled by said 10 called line for substituting the small for the large capacity condenser.

7. In a telephone system, a calling line, a called line, means including an operator's 15 cord circuit, a repeating trunk circuit having inner and outer sections and automatic switches for establishing a connection between said lines, an impulse sender for said 20 cord circuit, condensers of large capacity normally connecting the inner and outer sections of said trunk circuit, small capacity condensers normally disconnected from the 25 inner and outer sections of said trunk circuit, operator controlled means for disconnecting said large capacity condensers from said trunk circuit and substituting therefor said small capacity condensers, and means controlled by said called line for disconnecting 30 said small capacity condensers and substi-

tuting said large capacity condensers therefor.

30

8. In a telephone system, a calling station, a called station, means including a link circuit and a trunk circuit for interconnecting said stations, capacity in said trunk circuit, means responsive to the connection of the 35 link circuit with the trunk circuit for varying the capacity of the trunk circuit, and means controlled by the called subscriber for varying the capacity of the trunk circuit.

9. In a telephone system, a calling station, a called station, means including a cord 40 circuit terminating in a plug and a trunk circuit terminating in a jack for interconnecting said stations, capacity in said trunk circuit, means responsive to the connection 45 of the plug of the cord circuit with the jack of the trunk circuit for varying the capacity of the trunk circuit, and means automatically operating in response to the answering of the called subscriber to again vary the 50 capacity of the trunk circuit.

In witness whereof, I hereunto subscribe my name this 26th day of August, A. D., 1920.

CLARENCE B. FOWLER.
